UNITED STATES PATENT OFFICE.

JOSEPH H. LEHMAN, OF PHILADELPHIA, PENNSYLVANIA.

DESIGN FOR A LANTERN-BODY.

SPECIFICATION forming part of Design No. 25,064, dated January 21, 1896.

Application filed August 20, 1895. Serial No. 559,960. Term of patent 14 years.

To all whom it may concern:

Be it known that I, JOSEPH H. LEHMAN, a citizen of the United States, residing in the city and county of Philadelphia and State of Pennsylvania, have invented and produced a new and original Design for a Lantern-Body, of which the following is a specification, reference being had to the accompanying drawings, of which—

10 Figure 1 is a top plan view. Fig. 2 is a side elevation.

The design relates principally to the cylinder or case, and especially to the upper portion thereof, and also to the oil-receptacle and base.

15 In the drawings, *a* designates the case or cylinder, *a'* its top portion, and *b* the oil-receptacle. The top portion *a'* has a convex upper surface in which is a central orifice *a²*.

20 Surrounding this orifice is a projecting cylindrical portion *a³*, and radiating from this cylindrical portion down to, or near to, a peripheral bead *f* are a series of escallops *e*.

Below the bead *f* the portion *g* is incurved to 25 a plain cylinder portion *h*, whose lower edge portion is beaded, as indicated at *i*. A series

of apertures *j* appear in the incurved portion *g*. Below the bead *i* is a reduced cylinder portion *i'*.

The part *a* in general outline is a plain 30 cylinder, from the front portion of which projects the usual cone *c*. At the opposite side, near its lower end, are projections *d d'*. Near its upper and lower ends are raised beads.

The oil-receptacle has a plain bottom, as 35 indicated in Fig. 2, and its upper portion has surrounding beads, grooves, or fillets *bb'*. The lower portion thereof is curved into convex form below the bead *b'*, and is ornamented by a series of radial escallops or moldings *b³*, 40 as indicated in Fig. 2.

m m' are laterally-projecting portions.

What I claim is—

The design for a lantern body, substantially as herein shown and described.

45 In testimony whereof I have hereunto affixed my signature in the presence of two subscribing witnesses.

JOSEPH H. LEHMAN.
